Primary Examiner — Wendy L Arminio(74) *Attorney, Agent, or Firm* — Nancy J. Flint, Attorney At Law, P.A.; Nancy J. Flint, Esq.(57) **CLAIM**

The ornamental design for a can and bottle holder, as shown and described.

DESCRIPTION

FIG. 1 is a front perspective view of a can and bottle holder showing my new design;

FIG. 2 is a left side view of the can and bottle holder;

FIG. 3 is a front view of the can and bottle holder;

FIG. 4 is a rear view of the can and bottle holder;

FIG. 5 is a top view of the can and bottle holder;

FIG. 6 is a bottom view of the can and bottle holder;

FIG. 7 is a cross-sectional view of the can and bottle holder taken in the direction of line 7-7 in FIG. 5; and,

FIG. 8 is a left side view of the can and bottle holder shown in a position of use on a human hand and holding a beverage can, both of which are drawn in broken lines and not claimed.

Right side view not shown is a mirror image of the left side view. The broken lines illustrating a human hand and beverage can in FIG. 8 depict environment and form no part of the claimed design.
